To all whom it may concern:

Be it known that I, Clarence P. Fisken, a citizen of the United States and a resident of Detroit, county of Wayne, State of Michigan, have invented a new, original, and ornamental Design for a Helmet, of which the following is a specification, reference being made to the accompanying drawing, forming a part thereof.

In the drawing:

from a position in front thereof.

3—3 of Figure 1.

I claim:

The ornamental design for a helmet, as shown.
